Patented Mar. 2, 1926.

UNITED STATES PATENT OFFICE.

WALTER A. SELTMANN, OF PASSAIC, NEW JERSEY.

DEVICE FOR SUPPORTING FLEXIBLE TUBES.

Application filed June 5, 1923. Serial No. 643,486.

To all whom it may concern:

Be it known that I, WALTER A. SELTMANN, a citizen of the United States, and residing at Passaic, in the county of Passaic and State of New Jersey, have invented certain new and useful Improvements in Devices for Supporting Flexible Tubes, of which the following is a specification, such as will enable those skilled in the art to 10 which it appertains to make and use the same.

This invention relates to devices for supporting flexible tubes or other elongated bodies in an upright or vertical position on 15 a table, shelf or other support; and the object of the invention is to provide a device of the class specified which is detachably mounted in connection with one end of the tube or other body to be supported; a further object being to provide the supporting 20 device with a closure member for the discharge spout of the tube, said closure member being formed integral with said device; and with these and other objects in view, the 25 invention consists in a device of the class and for the purpose specified, which is simple in construction, efficient in use, and which is constructed as hereinafter described and claimed.

30 The invention is fully disclosed in the following specification, of which the accompanying drawing forms a part, in which the separate parts of my improvement are designated by suitable reference characters in 35 each of the views, and in which:—

Fig. 1 is a side view of a flexible tube with part of the construction broken away and showing one of my improved supporting devices mounted in connection therewith 40 and in section.

Fig. 2 is a sectional view of a modified form of supporting device and indicating a part of a tube mounted thereon.

Fig. 3 is a perspective view of another 45 form of supporting device.

Fig. 4 is a perspective view of another modification which I may employ.

Fig. 5 is a view similar to Fig. 2 but showing another modification.

50 Fig. 6 is a view similar to Fig. 1 but showing a modification and with part of the construction omitted; and,

Fig. 7 is a view similar to Fig. 6 but showing another modification.

55 In Fig. 1 of the drawing I have shown at 10 a flexible tube which may contain a

dental cream, medicinal preparations, paints or the like, said tube being closed at one end as shown at 11 and the other end being slightly conical in form as shown at 12 and 60 provided centrally with an internally threaded discharge member 13, and at 14 I have shown one form of supporting device which I may employ.

The supporting device 14 shown in Fig. 65 1 comprises a concavo-convex disk-shaped body portion 15 having a plurality of depending leg members 16, and centrally of the body 15 is a downwardly directed internally threaded nut member 17 formed integral 70 with the body 15 as clearly shown. The nut member 17 is adapted to be threaded upon the discharge member 13 of the tube, and serves as a closure for said member as clearly 75 shown in Fig. 1 of the drawing.

In Fig. 2 of the drawing, I have shown a supporting device 18 composed of a concavo-convex body portion 19 having depending leg members 20 and upwardly directed 80 spring members 21 intermediate of said leg members. The spring members 21 are adapted to engage the periphery of a tube 10 as indicated in dot and dash lines, for holding the same in position and also for retaining the device 18 in connection with the 85 tube. In this construction, the body portion 19 is provided centrally with an aperture 22 through which the threaded discharge 90 member 13 of the tube 10 is adapted to pass, and with this construction the usual closure cap 23 for the tube is employed.

In Fig. 3 of the drawing, I have shown a modified form of supporting device comprising a cup-shaped member 24 provided centrally with an aperture 25 adapted to 95 receive the threaded discharge member 13 of the tube. In Fig. 4 of the drawing, I have shown another form of the device comprising a base having three outwardly and downwardly curved leg members 26, and 100 centrally of the top portion of the base is an upstanding internally threaded sleeve member 27, into which the threaded discharge member 13 of the tube is adapted to be placed.

In Fig. 5 of the drawing I have shown another form of supporting device 28 comprising a ring body portion 29 having a plurality of depending leg members 30, and intermediate of the leg members the body 29 is 110 bent inwardly to form flanges 31 upon which the flexible tube 10 is adapted to rest when

placed in the supporting device, and with this construction the usual closure cap 23 is employed in connection with the tube 10.

In Fig. 6 of the drawing, I have shown 5 at 32 another supporting device which is substantially similar to the device 14 shown in Fig. 1 except that the body portion 33 thereof is provided at its periphery with a downwardly directed annular sleeve portion 34, instead of the leg members 16, and the body portion 33 is provided centrally with a downwardly directed nut or closure member 35 similar to the member 17.

In Fig. 7 of the drawing, I have shown 15 at 36 a body portion which is internally threaded at its opposite ends as shown at 37 and 38 to receive the threaded discharge 13 of the tube 10 and centrally of the body 36 is an annular recess 39 in which one end 20 of a conical spring 40 is secured, and the spring 40 in conjunction with the body portion 36 serves as a supporting device for the tube 10 as shown in full lines, and said device may be attached to the tube 10 as indicated in dotted lines in said figure.

With all of the construction shown, it will be noted that I provide a supporting device which is detachably mounted in connection with the discharge end portion of a flexible 30 tube and which serves to support said tube in a vertical position with the discharge end thereof directed downwardly, and in the construction shown in Figs. 1, 4, 6 and 7 the supporting device also serves as a closure 35 for the discharge member or the tube and takes the place of the usual closure cap. With all the forms of construction shown, the supporting devices will operate to retain a tube in the desired position and may 40 be detached from the tube when it is desired to discharge a portion of the contents thereof or may be retained upon the tube and the usual closure cap removed, for this purpose, as with the construction shown in 45 Figs. 2 and 5 of the drawing.

By the use of my improved supporting devices, it will be apparent that a tube of the class specified may be supported in a neat, attractive position as well as a position 50 which will occupy the least amount of space on a shelf or other support, and while I have shown certain details of construction for carrying my invention into effect, it will be understood that I am not necessarily limited to these details and various changes 55 therein and modifications thereof may be made within the scope of the appended

claims without departing from the spirit of my invention or sacrificing its advantages.

Having fully described my invention, 60 what I claim as new and desire to secure by Letters Patent, is:—

1. A device for supporting a flexible tube in an upright position, said tube comprising a body portion provided at one end with 65 a discharge spout, and said device comprising a body portion fashioned to receive said spout and provided at the periphery thereof with means depending in a direction away from said tube and projecting beyond 70 the discharge end of the spout and of substantially the same transverse dimensions as the corresponding dimensions of said tube and adapted to be placed on a suitable support for supporting said tube in an upright 75 position.

2. A device for supporting flexible tubes in an upright position comprising a body in the form of a concavo-convex plate member adapted to form a seat and support for 80 one end of a flexible tube mounted thereon, said body being provided with an internally threaded thimble-shaped part projecting from the convex face thereof and into which the threaded discharge spout of the tube is 85 adapted to be placed, and the periphery of said body being provided with a plurality of leg members extending in a direction from the convex face thereof and in substantial alinement with the periphery of the 90 tube mounted in connection therewith, said leg members projecting beyond said thimble-shaped part.

3. A device of the class described adapted 95 to be detachably mounted in connection with the discharge end portion of a flexible tube for supporting the tube in an upright position, said device comprising a body portion upon which one end of the tube rests when mounted in connection therewith, and means 100 depending from said body portion in a direction away from the tube when mounted thereon for supporting the tube in upright position, said means being of substantially the same transverse dimensions as the corresponding 105 dimensions of said tube and projecting beyond the discharge end of the tube when the same is mounted in connection with said body portion.

In testimony that I claim the foregoing 110 as my invention I have signed my name this 26th day of May 1923.

WALTER A. SELTMANN.
